COMBINATION CARDBOARD BOX OPENER
AND SPOUT

John Thomas Cooney, Los Angeles, Calif.

Application March 21, 1934, Serial No. 716,669

6 Claims. (Cl. 221—11)

This invention is a detached spout device for application to, and ready removal from, a cardboard-wall carton or receptacle.

An object is to provide a spout device incorporating its own cutter, whereby the cardboard wall of a container may be accurately and cleanly incised at any desired location on the wall to form an opening which will substantially conform, in part of its outline, to the spout forming element of the device, and form a flap hinging integrally at one of its sides on the wall so as to open and close at the cut opening.

A further purpose is to provide unitary means for detachably securing the spout unit in place on the formed flap.

Another object is to provide a spout device whose parts are so constructed and arranged and so effective as to make a kerf and form a flap which, when opened, will uncover a spout element and permit the contents of the container to be freely poured, and when the flap is closed it will fit so close as to preclude ingress of dust and insects.

A desideratum is to provide a unitary element in the device which will serve as a lift for application of a finger to open the closed flap, and, in addition, will serve to stop the flap in closed position in the plane of its wall.

Generally, it is an object to provide a combined opener and spout device of integral, rigid and substantial structure; which may be distributed gratuitously as an advertising novelty for use on divers containers of various kinds of contents, of dry state and capable of flowing through an aperture in the container.

An object is to provide a device of the kind here disclosed that is of simple and ready operation for cutting the wall; is of easy application to and removal from the produced wall flap; and of low cost and long effective life.

The invention consists of certain advancements in this art as set forth in the ensuing disclosure and having, with the above, additional objects and advantages as hereinafter developed, and whose construction, combination and details of means, and the manner of operation will be made manifest in the description of the herewith illustrative embodiment; it being understood that modifications, variations and adaptations may be resorted to within the scope, principle and spirit of the invention as it is more directly claimed hereinafter.

Figure 1 is a perspective of the detached device.

Figure 2 is a face elevation of the device ap-

plied in cutting position on a wall of a carton, and

Figure 3 is an edge view thereof.

Figure 4 is a partial section of a carton showing the device applied to the inner face of the cut flap, and in closed position.

Figure 5 is a perspective showing the flap pulled open to draw the concealed spout out to useful position.

Figure 6 shows the flap cut at the bottom of the container for special use of the device.

Figure 7 is an elevation, partly sectioned, of a modified form of opening-movement stop.

The device comprises a semi-disc 2, of any desired size, having on its central radius a sharp spindle 3 projecting from the diametrical edge 4 so that the spindle point can be punched into a cardboard wall W, Fig. 2, of a carton C, and thus form an axis of rotation for the up-standing semi-disc part 2, which may be regarded as a handle for rotational purposes.

Extending from one face of the disc part 2 is a segment 5 of a conical annulus with its base on the plane normal to the edge 4 of the part 2. The basal radius of the segment 5 is about equal to that of the semi-disc and at one end of the edge 4 is a sharp cutter 6 projecting parallel to and unidirectionally with the spindle 3. When the spindle is pressed into the wall W, Fig. 5, with the cutter 6 located at point P and pressed into the wall, then if the device is turned 180 degrees clockwise a semi-circular kerf will be cut which is of the same radius as is the base line of the segment 5. Figs. 2 and 3 show the cutting position of the device on the outer face of the wall W.

The device is removed when the half-circle kerf is completed and the cutter 6 is used as a pry to lift up the semi-circular flap F so that it bends along the hinge line H, Fig. 5, and then the device is arranged with the semi-disc 2 flat against the inner face of the flap, Fig. 4.

The part 2 has, at the middle of its arcuate edge 7, an inturned spur 8 doubled on itself at 9 and thence continued somewhat beyond the outer face of the part 2 and being bent outward at a right angle to form a finger lift 10. From this lift there is bent inward, over the semi-disc 2, a spring finger 11, this being provided as a means to grip on the flap when this is inserted between the finger 11 and the semi-disc part 2.

When the semi-disc is thus arranged on the under face of the flap F and the finger 11 grips

on the flap top the extension 10 will lap on the wall W when the flap F is closed, Fig. 4, and stop its inward movement so that the kerf space will be practically obliterated and ingress of dust and insects precluded.

To open the spout the flap F is swung open by application of a finger under the lift 10 and as the flap is pulled up the segment 5 comes forward to lap on and along the wall opening edge O.

Outward movement of the flap and the spout thereon is limited by a suitable means such as a set of marginal prongs 12 bent outward in the base of the segment 5. Fig. 7 shows a stop in the form of a slight, basal flange 13.

To facilitate spoon-full measuring, the spout opening can be cut in the lower part of a wall of a container, as in Fig. 6.

The device is preferably made of sheet metal cut, shaped and completed as an integral implement. When the cartons are sold with the device as a part of its structure it is possible to remove the device and use it as a cutter and spout on any other desired container with a cardboard wall.

What I claim as new is:

1. A combined carton flap cutter and pouring spout device including a body and a handle forming part with a medially disposed pointed spindle to be punched into a carton wall to form an axis of rotation, a cutter fixed on said body and adapted to be pressed into the said wall and to cut a curved kerf and form a flap about said axis when the handle part is rotated; said part provided with a segmental element complementary to the cut kerf to form a spout, and means cooperative with the handle part for clamping the spout segment to the cut flap.

2. A combined carton flap cutter and pouring spout device including a handle forming member with a pointed spindle to be punched into a carton wall to form an axis of rotation, a conoidal segment whose ends are fixed to the said handle part, and a cutter fixed on the segment in such relation to said spindle as to cut a kerf about said spindle complementary to the curve of said segment and at the same time form a flap in the wall, and said handle having means coacting therewith for detachably clamp-

ing the device onto the flap with the spout segment on the inner side thereof.

3. A combined carton flap cutter and pouring spout device including a conoidal segment, a handle part with a pointed spindle to be punched into a wall of a carton to form an axis of rotation for the device, a cutter fixed to the segment and adapted when the handle is turned to cut a kerf complementary to the segment and form a wall flap about said axis, a finger lift part attached to the handle to facilitate opening the spout to pouring position, and means coacting with the handle for attaching the device to the flap with the segment on the inner side thereof.

4. A combined carton flap cutter and pouring spout device including a segment of an annulus and a handle forming part to which it is fixed, an axis forming spindle attached to and about which the said part may be rotated, a cutter fixed on and adapted to cut a kerf complementary to the segment by rotation of the handle, and means cooperating with said handle part for removably attaching the annulus to the inner side of the flap.

5. A cutter and carton spout device having a body with a spindle to be punched into a carton wall and form an axis of rotation, a conical segment fixed at its ends to said body, a cutter fixed to the body as to cut a kerf complementary to the segment when the body is turned, and means for attaching the segment to the inner side of the cut flap in spout forming position as to the opening made when the flap is pulled outward and including a finger overlapping and attached to the said body.

6. A cutter and carton spout device having a handle forming part with a spindle, a conical segment fixed at its ends to said part, a cutter fixed on the segment to cut a kerf complementary to the segment when the cutter is turned about said spindle, means cooperating with the handle part for attaching the device to the cut part of the wall of a carton so that the segment will form a spout at the opening when the wall part is pulled outward, and means to facilitate opening of the said wall part and to stop its closing movement.

JOHN THOMAS COONEY.
